United States Patent Office

Des. 222,611
Patented Nov. 16, 1971

222,611

BOTTLE

Gordon A. Strand, Toledo, Ohio, assignor to
Owens-Illinois, Inc., Toledo, Ohio

Filed Dec. 4, 1970, Ser. No. 26,290

Term of patent 14 years

Int. Cl. D9—01

U.S. Cl. D9—116

FIG. 1

FIG. 2

FIG. 3

FIG. 4

FIG. 1 is a perspective view of a bottle showing my new design;

FIG. 2 is a front elevational view thereof, the opposite side being the same in appearance as the side shown;

FIG. 3 is an end elevational view thereof, the opposite side being the same in appearance as the side shown;

FIG. 4 is a top plan view thereof.

I claim:

The ornamental design for a bottle, substantially as shown and described.
